VENTING CLOSURE AND LINER THEREFOR

Edward L. Dryer, Lancaster, Pa., assignor to Armstrong Cork Company, Lancaster, Pa., a corporation of Pennsylvania

Application September 24, 1948, Serial No. 51,070

2 Claims. (Cl. 215—56)

1

This invention relates to venting closures, more particularly, the invention relates to a venting closure having a liner capable of venting excess pressure developed in a container having the closure applied thereto.

In the packaging of certain products, particularly bleaching solutions such as sodium hypochlorite, hydrogen peroxide, and the like, and bleaching powders such as calcium hypochlorite, there is a problem presented by the development of pressure within containers holding such materials, which pressure may be due to the presence in the material of impurities, such as small amounts of iron, copper, or organic material, which impurities cause decomposition of the products resulting in the evolution of gas which develops pressure in the container. The development of pressure may also be caused by storage of such containers in places in which they are subjected to elevated temperatures as the application of fairly high temperatures to such materials also results in decomposition of at least a portion of the material resulting in the evolution of gases therefrom.

Pressure development within such containers is a definite hazard as excessive pressures have oftentimes resulted in sudden disintegration of the container with an explosive force which may have very harmful effects. In addition, in many instances wherein pressure has developed and has not been relieved, sudden opening of the package results in a rapid discharge of its contents due to comparatively high pressures within the package.

Various closures known to the art as venting closures have been proposed and used to overcome the problem of pressure development within this type of package. These venting closures are, generally speaking, quite complicated and difficult to manufacture and, for that reason, only a few of them have been employed commercially in an attempt to overcome the problem of pressure development. While closures have been developed which vent gas upon the development of comparatively high pressures within the container, there is also the problem of liquid leakage due to ineffective sealing. Since some sort of valve must be present to enable venting of the closure to release the gases developed through decomposition or other reactions within the package, leakage through such valve arrangements often occurs, particularly in those instances wherein the material packaged is normally in the liquid phase. Generally speaking, it is desirable to provide a venting closure which

2

vents so as to relieve excess pressure at a pressure of 10 to 15 pounds per square inch. In some instances, depending upon the particular product, the design of the container or package, and 5 the like, venting at pressures of 5 to 10 pounds per square inch is desirable. An acceptable venting closure should vent up to pressures as high as those indicated above and should also have a valve action so that, upon release of the pressure, there will be a sealing off of the remaining contents of the container to which the closure is applied.

In addition to the above-discussed problems of venting, while at the same time providing a seal 15 after release of pressure, there is the requirement that such a closure be capable of convenient manufacture.

It is, accordingly, an object of this invention to provide a closure which is capable of relieving 20 pressure developed in containers or packages for material which develops pressure under certain conditions.

A further object of this invention is the provision of a liner which may be employed in conjunction with a conventional closure, thereby rendering it capable of venting upon the development of pressure within a container to which it is applied with a minimum risk of leakage.

Still another object of this invention is to provide a venting closure, the parts of which may be conveniently assembled in conventional equipment. These and other objects of this invention will become apparent to those skilled in the art upon becoming familiar with the following description when taken in conjunction with the accompanying drawing in which:

Figure 1 is a perspective view of a laminated sheet from which liners are punched in accordance with one embodiment of my invention;

Figure 2 is a bottom plan view, with a portion broken away, of a liner punched from the sheet of Figure 1;

Figure 3 is a perspective view of a laminated sheet made in accordance with another embodiment of my invention;

Figure 4 is a sectional view of a cap containing the liner of Figure 2 and applied to the neck of a container;

Figure 5 is a view similar to Figure 4 illustrating the manner in which venting occurs upon the development of pressure within the container; and

Figure 6 is view similar to Figure 4 illustrating 55 a liner punched from the sheet shown in Figure

3 as part of a venting closure applied to a container.

In accordance with one embodiment of my invention, I provide a liner material such as is shown in Figure 1, which material comprises a resilient backing 2, an intermediate screen layer 3, and a facing layer 4. The sheet shown in Figure 1 may be manufactured by any means known to the art, but preferably by adhesively securing the screen 3 as an intermediate layer to the backing 2 and the facing 4. The adhesive 5 may be anyone known to the art such as casein type, glue and the like. The backing 2 may be of any material known to the closure liner art such as cork composition, pulpboard, newsprint, or other naturally occurring or synthetic materials having equivalent properties. The screen 3 is advantageously of a coarse mesh such as window screen and may be made of metal or any suitable plastic such as nylon, "Saran" (vinylidene chloride polymers), "Vinylite" (vinyl chloride polymers and copolymers), and the like. Generally speaking, it is desirable to employ a plastic material which possesses some resistance to acids, alkalies, and the like which may be encountered in the packing of various products. The facing 4 may be any one of a number of thin and flexible materials known to the art including "Vinylite," "Saran," "Pliofilm," metal foil, varnished paper, and the like.

After a sheet of laminated material having a plurality of separate laminae has been assembled as indicated above, it may be sliced into ribbons of desirable thickness and passed through punches from which a liner such as that illustrated in Figure 2 may be punched. Of course, if desired, the sheet itself may be passed through a plurality of punches properly spaced so as to obtain a liner of the desired dimensions.

If desired, in one embodiment of my invention, the backing material may be eliminated and the liner may comprise a heavy screen to which is adhered a suitable facing film of resistant material. The facing film may be any of the well-known facing materials mentioned above. Such a modification is illustrated in Figure 3 in which 3 designates a screen which functions as a backing to the facing film 4. After the liners have been punched in accordance with my invention, they may be inserted in a closure by means of an adhesive. Any adhesive commonly employed in closure assembly may be used such as protein adhesives, protein-rubber latex compositions, thermoplastic adhesives such as synthetic resin type adhesives, and the like. If desired, an adhesive may be dispensed with and a friction fit of the liner in the closure shell may be used. Generally speaking, it is advantageous to adhesively secure the liner to plastic closure shells and to utilize a friction fit in metal closure shells. Of course, in some instances, depending upon the type of package and the like, friction fit liners may be used in plastic shells and adhesively secured liners may be used in metal shells.

In Figure 4 is illustrated an assembled closure made in accordance with my invention applied to a container. The closure shell, which may be metal or a suitable plastic such as "Bakelite," polystyrene, and the like, contains a liner having a backing 2, an intermediate layer of screen 3, and a facing film 4. The laminated liner is secured to the shell 6 by means of adhesive layer 7. Figure 6 illustrates a modification in which a liner made from the sheet illustrated in Figure 3 is employed. The two-ply liner includes a back-

ing screen 3 and facing material 4. Ordinarily, a friction fit of the liner in the shell 6 is employed in this type of assembly.

The operation of the venting closures of my invention upon the development of pressure within a container to which it is applied is illustrated in Figure 5. As can be seen by reference to Figure 5, the pressure applied to the facing film 4 causes the film to flex around the cut edges of the screen 3, thereby permitting the pressure developing gases to escape and thus relieve the pressure within the container. Upon release of the pressure, the facing film because of its flexible nature, resumes its position in sealing relationship with the lip of the container. It is to be understood, however, that I do not intend to be limited by any theories expressed herein.

The closures and the liners therefor made in accordance with my invention are comparatively simple to manufacture and to assemble. The liner may be manufactured by conventional techniques, and the closure may be assembled in conventional equipment. The resulting product is a venting closure which is capable of venting upon the development of excessive pressure within a container and which is also capable of substantially completely resealing the container contents upon release of pressure within the container.

While my invention has been described with reference to certain particular embodiments and with reference to certain specific examples, it should be understood that my invention is not limited thereby. Therefore, changes, omissions, substitutions and/or additions may be made without departing from the spirit of the invention as defined in the appended claims which are intended to be limited only as required by the prior art.

I claim:

1. In combination with a container, a venting closure including a shell having means for affixing the closure to a container and a liner adhesively secured thereto, said liner including a relatively thick and compressible backing, an intermediate layer of screen, and a relatively thin, flexible, and impervious facing film, the outer periphery of said layer of screen forming a plurality of openings capable of receiving said facing film upon the development of pressure within the container.

2. In combination with a container, a venting closure comprising a closure shell having means for affixing said closure to a container, a liner in said closure including a relatively coarse screen having adhesively secured thereto a facing film of relatively thin, flexible, and impervious plastic material, the outer periphery of said screen forming a plurality of openings capable of receiving said film upon the development of pressure within said container.

EDWARD L. DRYER.
